UNITED STATES PATENT OFFICE.

LAMARTINE B. FAY, OF ELYRIA, OHIO.

HEEL AND SECURING MEANS THEREFOR.

Application filed June 26, 1922. Serial No. 570,858.

To all whom it may concern:

Be it known that I, LAMARTINE B. FAY, a citizen of the United States, residing in Elyria, county of Lorain and State of Ohio, have invented certain new and useful Improvements in Heels and Securing Means Therefor.

My invention relates more particularly to metallic heels and to means for attaching the same to the bottom of the shoe. Heretofore means for securing such metal heels have been provided which have been more or less cumbersome, and unnecessarily expensive.

I contemplate a simplified construction in which the nails that attach the heel to the shoe may be removed if desired, which nails are held in place by pressing directly on the head of the nail. I also contemplate the use of metallic means acting directly upon the nail head, and exerting pressure in the direction of the length of the nail.

Among the objects of my invention, therefore, are the following—

To provide an improved heel with a series of cavities circumferentially arranged, and perforated at the bottom whereby the heel may be nailed through said perforations to the shoe, the nail heads being retained in the cavity;

To provide plugging means in said cavity over said nail head for holding the nail in place;

To provide a heel of the above character in which said plugs are used in said cavity for directly engaging the nail head to clamp the same in place and prevent its creeping out;

To provide plugs of the above character which may be removed from the cavity to remove the nail, and which plugs exert pressure directly upon the nail head in the longitudinal direction of the nail;

To provide other details of improvement tending to increase the efficiency and serviceability of a metallic heel and attaching means therefor;

To accomplish the foregoing and other useful ends, my invention makes use of means hereinafter more fully set forth and claimed.

Referring more in detail to the accompanying drawing—

Fig. 1 is a top view of the heel.

Fig. 2 is a sectional elevation of a heel on line 2—2, Fig. 1.

Fig. 3 is a similar view showing the heel supporting bridge plate in place.

Fig. 4 is a top view of the heel with the bridge plate in place.

Fig. 5 is a view of the heel similar to that shown in Fig. 2, showing a modified form of the plug for holding the nail in place.

Referring more in detail to the drawing, the heel is hollow and the upper extremity is slanted to accommodate the usual slope 65 of a lady's foot. The heel may be made of any suitable metal, aluminum or aero-metal and the like, for example. Along the upper rim of the heel the metal expands into a 70 series of bosses 2, Fig. 2, which are correspondingly tilted.

From the rear of these bosses, and circumferentially arranged about the heel, I have a series of cavities, one projecting into 75 each one of said bosses. From the bottom of these bosses I have perforations large enough to permit a shoe nail 3 to pass through, but not large enough to permit the head 4 to pass through, as shown in the 80 drawing. These nails project beyond the limit of the heel, and extend of course into the shoe. Resting on the bosses as a shelf I provide a plate 5 which receives the weight 85 of the wearer's heel when the shoe is being worn.

In order to nail the heel in place, it is put in position under the shoe, and the nails 3 after being inserted in the perforations, are driven home in any suitable manner, 90 as, for example, by the use of a blunt awl, or some other suitable tool.

As shown in Fig. 2 the sides of the cavities are threaded to receive studs such as stud 6. Stud 6 may be screwed home until 95 it strikes the head 4 of the nail, serving to lock the nail in place by a direct thrust on the nail head in the direction of length of the nail. In other devices some sort of clamping means have been used in which the 100 thrust is from the side. This old arrangement is more cumbersome and requires more parts. It will be seen that if it ever becomes necessary to remove the nails, or to replace them, the studs 6 may be removed, 105 and the nails pulled out or driven out.

In Fig. 5 I show a modification of the plug. The cavity also is much smaller and this cavity is filled up by casting a molten metal right in the cavity.

Referring to Fig. 2, I wish to point out that after the stud 5 is in place, the cavity

above the stud may be filled up with any suitable material forming a plug 7 which will make the surface of the heel smooth. This plug can, of course, be lifted out when it is desired to unscrew the plug 5.

It will thus be seen that I provide an efficient, simple, compact arrangement in which the clamping means is reduced to a single element, namely, the plug 6 which latter acts directly upon the nail without the necessity of interposing any additional elements.

What I claim as my invention is—

1. A metallic shoe heel having a series of cavities about the circumference of said heel upwardly projecting into the metal, each cavity containing a perforation through its bottom extending from the cavity through the metal to the upper surface of the heel, 20 nails for securing said heel to the bottom of a shoe, said nails projecting through said perforations and extending beyond the heel, said perforations being smaller than the heads of the nails, and a metal plug in each 25 cavity between the nail and the mouth of the cavity for clamping the nail in place.

2. A metallic shoe heel having a series of cavities about the circumference of said heel upwardly projecting into the metal, 30 each cavity containing a perforation through its bottom extending from the cavity through the metal to the upper surface of the heel, nails for securing said heel to the bottom of a shoe, said nails projecting through said 35 perforations and extending beyond the heel, said perforations being smaller than the heads of the nails, and a metal plug in each cavity between the nail and the mouth of the cavity for clamping the nail in place, 40 said plug in direct contact with the said nail.

3. A metallic shoe heel having a series of cavities about the circumference of said heel upwardly projecting into the metal, 45 each cavity containing a perforation through its bottom extending from the cavity through the metal to the upper surface of the heel,

nails for securing said heel to the bottom of a shoe, said nails projecting through said perforations and extending beyond the heel, 50 said perforations being smaller than the heads of the nails, and a metal plug in each cavity between the nail and the mouth of the cavity for clamping the nail in place, 55 said plug and cavity walls in threaded engagement with each other.

4. A metallic shoe heel having a series of cavities about the circumference of said heel upwardly projecting into the metal, 60 each cavity containing a perforation through its bottom extending from the cavity through the metal to the upper surface of the heel, 65 nails for securing said heel to the bottom of a shoe, said nails projecting through said perforations and extending beyond the heel, said perforations being smaller than the heads of the nails, and a metal plug in each cavity between the nail and the mouth of the cavity for clamping the nail in place, 70 threads on said plug and on the walls of the cavity whereby the plug may be secured to the heel to clamp the nail in position, the threads in the walls so disposed with respect to the nail that by screwing the plug into place, the plug moves along a 75 line extending in the direction of the length of the nail.

5. A metallic shoe heel of generally upwardly bearing external form having an upwardly directed cavity disposed near the 80 upper rim thereof, a perforation through the top wall of said cavity whereby the heel may be nailed through said perforation to the shoe, and clamping means screw-threaded into said cavity for clamping the nails in 85 position to prevent them from creeping out of the perforation, said clamping means operating directly on the head of the nails and exerting pressure in the direction of 90 the length of the nail.

In witness whereof I have hereunto signed my name this 23d day of June, 1922.

L. B. FAY.
